UNITED STATES PATENT OFFICE.

A. JOSEPH BROUILLARD, OF BRISTOL, CONNECTICUT.

LINE-HITCHING DEVICE.

SPECIFICATION forming part of Letters Patent No. 365,965, dated July 5, 1887.

Application filed February 24, 1886. Serial No. 193,083. (No model.)

To all whom it may concern:

Be it known that I, A. JOSEPH BROUILLARD, of Bristol, in the county of Hartford and State of Connecticut, have invented a certain new and useful Improvement pertaining to Line-Hitching Devices, of which the following is a description, reference being had to the accompanying drawing, where the figure is a view of the device embodying my improvement.

10 As the title of this improvement indicates, it is a line-hitching device.

The letter *a* denotes a base or frame on which the other operating parts are attached.

15 The letter *b* denotes a pulley, fixed or rotary, preferably the latter, grooved on its edge for the purpose of retaining a line.

The letters *c* denote two duplicate eccentrics rotarily pivoted on the pivot-pins *d*, and grooved upon the edges in order to retain the 20 line.

The letter *e* denotes a pin, the use and pres-

ence of which may be desirable in some adjustments of the line. It will be readily understood that a pull upon either end of the line will have a tendency to pull one of the eccentrics *c* into closer relations with the pulley *b*, thereby jamming the line between the eccentric and the pulley, so that it will be held tightly. The base or frame *a* is of course to be attached to some proper support, and all parts, except the rope, are by preference metallic.

25 I claim as my improvement—

A combination of the grooved pulley *b* and the duplicate eccentric pulleys *c*, all substantially as described, and for the purpose set forth.

35 A. JOSEPH BROUILLARD.
